UNITED STATES PATENT OFFICE

2,214,620

CIRCUIT INTERRUPTER

Winthrop M. Leeds, Wilkinsburg, Pa., and Ennio Ortensi, Bergamo, Italy, assignors to Westinghouse Electric & Manufacturing Company, East Pittsburgh, Pa., a corporation of Pennsylvania

Application May 25, 1937, Serial No. 144,626

20 Claims. (Cl. 200—150)

This invention relates to circuit interrupters, and more particularly to circuit interrupters of the liquid immersed type.

In United States Patent No. 1,899,605, issued February 28, 1933, to E. P. Baker and E. G. Kees, and assigned to the assignee of this application, is described a circuit interrupter of the liquid immersed type having an arc extinguishing structure consisting of a stack of slotted plates of insulating material interspersed with slotted plates of magnetic material. The slots in the respective plates are open at one end and aligned so as to form a passage or groove in which an arc may be drawn. The arc is drawn within the passage adjacent the open side thereof and caused to be moved inwardly by the magnetic reaction resulting from the distorted magnetic field set up by the slotted plates of magnetic material.

The action of the arc during its movement through the arc extinguishing liquid produces a gas composed largely of relatively cool un-ionized particles, which is caused to flow through the arc stream and escape along the open side of the arc passage. In flowing through the arc stream, the un-ionized particles are turbulently intermixed with the ionized particles which sustain the arc. This intermixing causes the arc stream to become less and less conducting so that when current zero is reached in the current wave, deionization has progressed sufficiently to prevent the arc from restriking as the voltage builds up in the opposite direction following current zero.

Arc interruption has been materially improved by substantially completely enclosing the arc passage, as shown and described in United States Patent No. 1,991,901, issued February 19, 1935, to W. M. Leeds and assigned to the assignee of this application. The improvement is effected by the provision of vent openings so positioned with respect to the arc passage that the arc stream is subjected to the combined effect of a longitudinal and a cross blast of gas.

Although the operation of the arc extinguisher of the type shown in the aforesaid Patent No. 1,991,901 represents a material improvement over the operation of devices prior thereto, we have discovered that further improvements may be made whereby better operation is obtained over a broader range of current values. Particularly at low current values the arc does not readily transfer from the main contact to the arcing horn on account of the relatively weak magnetic pull set up by the slotted plates of magnetic

material interspersed between the plates of insulating material forming the side walls of the arc passage. The arc, therefore, remains adjacent the arc drawing contacts within a low pressure gas-filled pocket formed by the high speed movement of the movable contact to the open position. This pocket contains largely ionized particles thereby making arc extinction more difficult. We have found that this difficulty can be overcome by injecting additional arc extinguishing liquid under pressure into the arc passage and through the arc stream, which greatly increases the ratio of un-ionized to ionized particles and thus hastens arc extinction.

The main object of our invention, therefore, is to improve the operation of circuit interrupters of the type above described.

A further object of our invention is to provide a circuit interrupter having improved performance over a broad range of current values.

A more specific object of our invention is to provide means in a circuit interrupter of the liquid immersed type for causing a more rapid deionization of the arc stream.

Other objects relate to details of the structural arrangement peculiarly adapted for the accomplishment of the above-named objects and which will appear more fully in the following description and the accompanying drawings, in which:

Fig. 1 is a side elevation partially in section showing a circuit interrupter embodying our invention;

Fig. 2 is a sectional view taken along line II—II of Fig. 4, showing one of the arc extinguishing units of our invention;

Fig. 3 is a sectional view of one of the arc extinguishing units taken along the line III—III of Fig. 4;

Fig. 4 is an end elevation view of one of the arc extinguishing units forming part of the circuit interrupter of our invention;

Figs. 5 to 16, inclusive, show details of the respective plate elements which constitute each of the arc extinguishing units;

Fig. 17 is an end elevation view showing the actuating mechanism for the arc extinguishing structures of our invention;

Fig. 18 is a side elevation view of the actuating mechanism shown in Fig. 17;

Fig. 19 is a sectional view of the actuating mechanism in the closed circuit position taken along the line XIX—XIX of Fig. 17;

Fig. 20 shows the mechanism of Fig. 19 in the open circuit position;

Fig. 21 is a side elevation view of the mecha-

nism in the closed circuit position, to the left of section line XIX—XIX of Fig. 17 and viewed from the line XXI—XXI of Fig. 17;

Fig. 22 shows the mechanism of Fig. 21 in the open circuit position;

Fig. 23 is a side elevation view showing only the equalizing linkage in the closed circuit position of the mechanism shown in Figs. 17 and 18; and

Fig. 24 is a side elevation view of the equalizing linkage of Fig. 23 in the open circuit position.

Referring to Fig. 1 of the drawings, the reference numeral 1 designates a base, in this instance serving as the sole support for the circuit breaker structure and in which a suitable operating mechanism (not shown), may be housed. Upon the base 1 is mounted an insulator 3, which in turn supports a tubular housing generally indicated at 5, in which the circuit interrupter proper is contained.

The housing 5 comprises a central housing member 7, preferably of metal, in which an actuating mechanism, generally indicated at 9, is positioned. The housing 7 has two opposed circular end plates 11, to each of which an arc extinguishing unit, only one of which is generally indicated at 13, is secured. Each of the arc extinguishing units 13 is surrounded by a tubular pressure or strain member 15, of strong insulating material. The strain members 15 may be secured to the end plates 11 by means of flanges 17 secured to one end of the members 15, and in turn bolted to the plate, as shown.

The outer end of each cylindrical strain member 15 may be closed by a plate 19 secured as by bolts 21, to a flange 23, secured to the outer end of the cylindrical strain members. A weather-proof shield 25 of porcelain or other suitable material, is disposed about each cylindrical strain member 15 and may be supported at one end from an end plate 11, and at the other end by a resilient metallic expansion member 27, which member in turn may be bolted to the plate 19, as shown. Thus, the strain members 15, acting through their respective expansion members 27, maintain the weather-proof shields 25 in position solely by subjecting the shields to compression.

Each of the arc extinguishing units 13, as more clearly shown in Figs. 2 to 4, comprises a plurality of plates of insulating material. The individual plates which comprise the stack are shown in detail in Figs. 5 to 16, inclusive. The right-hand plate 31, as viewed in Figs. 2 and 3, is shown in Figs. 15 and 16. It is preferably constructed of insulating material having considerable thickness and is provided with four apertures 33, screw-threaded for the reception of a tubular guide member 35, as more clearly shown in Fig. 3.

Adjacent the plate 31 is positioned a pair of plates 37 shaped as shown in Figs. 13 and 14, and also having apertures 33 extending therethrough and disposed so as to coincide with the apertures 33 in the plate 31, thereby permitting the assembly of these plates over the four guide tubes 35. Adjacent the plates 37 is a plate 39 having a configuration as shown in Figs. 7 and 8. The plate 39 and all succeeding plates are provided with the four apertures 33 for assembly upon the guide tubes 35.

Adjacent the plate 39 is a compound plate 41 as shown in Figs. 9 and 10, which comprises an outer portion 43 of insulating material and a U-shaped insert 45 of magnetic material. The

portions 43 and 45 are of the same thickness and are adapted to be disposed between two plates 39. The purpose of the magnetic insert 45 will be fully explained hereinafter.

Adjacent the plate 41 is positioned a second plate 39. The remaining plates comprise alternately a series of two plates designated 37 and a series of three plates designated 39, 41, 39, with the exception of the last six plates of insulating material. A pair of plates 41, as shown in Figs. 10 11 and 12, are similar to the plates 37 shown in Figs. 13 and 14, with the exception that the former plates have a recessed notch 49 in one end thereof to form a vent passage, the purpose of which will be more fully described hereinafter. 15

The next group of three plates in sequence is designated 51, 41, 51, the plates 51 being similar to plates 39 shown in Figs. 7 and 8, with the exception that they have an open slot shown at 53 in Fig. 2. The intermediate plate 41, however, 20 in this last-named series of three plates, is the same as previously described. The outermost plate of insulating material designated at 55 is substantially of the same thickness as plate 31 and is shown in detail in Figs. 5 and 6. In addition to the apertures 33, the plate 55 is provided with countersunk recesses 57 for the reception of a spanner nut 59, which nut is adapted to be threaded upon each of the guide tubes 35. It is thus seen that the four guide tubes 35, with 30 their respective nuts 59, serve to hold the entire stack of insulating plates in the assembled position.

It will be observed that the plates 39 and 41 are provided with an elongated slot 61, one end 35 of which is somewhat enlarged for a purpose which will be hereinafter described. The plates 37 and 41 are provided with a slot 63 similar in general outline to the slots 61 but which has, in addition, recesses or indentations 65 extending on 40 opposite sides thereof. It will be observed that the stack of plates arranged as shown in Figs. 2 and 3 provide for a slot-like arc passage 62, the cross-section of which is determined by the slot 61 which provides for an enlarged portion 45 67 and a restricted portion 69. The outermost plate 55 of insulating material also has a slot therethrough designated at 71, which slot is somewhat wider than the slot 61 in the plates 39 and 41. A portion of the opposed side walls of 50 the slot 71 is bevelled outwardly as shown at 73, the purpose of which will appear more fully hereinafter.

Adjacent the plate 55 is a metal head plate 75, which in this instance, may be secured to the stack of insulating plates by means of four tie rods 77, as more specifically shown in Fig. 3. The tie rods 77 are preferably of insulating material, one end of which is provided with a metallic flanged head portion 79 and the other end with 60 a threaded metallic portion 81. The tie rods 77 are adapted to pass through the end plates 11 of the housing 7 and through the tubular guide rods 35, thereby securely fastening the head plate 75 to the unit 13, which unit in turn is securely 65 fastened to the end plates 11. The head plate 75 is provided with a rectangular aperture 85 for the reception of a yieldingly mounted stationary contact 87.

The contact 87 is carried by a cylindrical body 70 portion 89, the left-hand end of which has a reduced guide portion 91. The guide portion 91 is adapted to pass through a bracket member 93 mounted transversely of the head plate 75 upon two spaced bolts 95 having one end screw- 75

threaded into the head plate 75. A spring 91 encircling the contact carrier 89 and interposed between the bracket 93 and the contact 87 biases the latter contact into the aperture 85.

5 Adjacent the aperture 85 and secured to the inner side of head plate 75 is an inclined arc horn 99. The arc horn 99 is adapted to project into the slot 71 of the plate 55 and is somewhat narrower than the slot. The arc horn 99 is electrically connected to the contact carrier 89 by a pair of flexible shunt connections 100, each having one end connected to the contact carrier 89 and the other end connected to the head plate 75.

10 The fiber plate 31, as well as the end plate 11 of the housing 7, is provided with a rectangular aperture 101 for the purpose of receiving a rectangular contact rod 103. The aperture 101 is in axial alignment with the aperture 85 in the head plate 75, hereby permitting the contact rod 103 to be moved slidably through the plates 11 and 31 into and out of engagement with the contact 87. In Fig. 2, the contact rod 103 is shown in the open circuit position. The contact 87 and the cooperating contact rod 103 are also disposed 15 in axial alignment with the enlarged portion 67 of the arc passage 62.

20 An arc established between the contact 87 and the contact rod 103 as a result of movement of the latter to the open position, will be moved laterally into the restricted portion 69 of the passage 62 as a result of a magnetic reaction set up by the arc in the U-shaped inserts 45 of magnetic material forming part of the composite plates 41. The magnetic pull exerted by the slotted plates 45 causes the left-hand end of the arc, as viewed 25 in Fig. 2, to transfer from the stationary contact 87 to the arc horn 99. Inasmuch as the arc extinguishing unit 13 is wholly immersed in arc-extinguishing liquid, the passage 62 as well as the pockets 65, will be filled with liquid and the arc drawn therein will decompose portions of the liquid forming quantities of relatively cool un-ionized gas. This gas escapes from the arc passage 62 by way of the recessed openings 49 30 provided in the plates 47 and also the slot openings 53 provided in the plates 51. It will be noted from Fig. 2 that any gas flowing towards these vent openings must necessarily pass through the arc stream and thus will be turbulently intermixed with the arc stream, causing rapid deionization thereof.

35 In order to hasten the deionization action during arc extinction, we have provided means for injecting additional arc-extinguishing liquid into the arc stream in a direction which is opposed to arc movement. In order to obtain this additional circulation of liquid in the arc chamber 62, we have provided the plates 31, 37, 39, 41, 47, 51 and 55 with circular apertures 105. The apertures 40 55 are positioned adjacent the ends of the slots in these plates and are adapted to receive a tubular member 107, preferably of insulating material, which may be screw-threaded at its right-hand end into the end plate 31. The left-hand end of 50 the tubular member 107 is provided with a slot 109 which is adapted to register with the slot 71 in plate 55 and the slot 61 in plates 51. The tubular member 107 serves as a cylinder wall and is adapted to receive a piston 111 mounted for 55 sliding movement therein and is actuated by a connecting rod 113.

60 It will appear more fully hereinafter in connection with the description of the actuating mechanism 9, that as the contact rod 103 is separated from the stationary contact 87, piston 111 is

6 moved to the left within the cylinder 107, thereby expelling the liquid contained therein through the slotted opening 109 into the arc chamber 62. This stream of liquid flows along the arc horn 99 through the arc, thereby increasing the turbulent intermixing of arc extinguishing liquid with the arc stream which further hastens deionization and consequently, arc extinction.

65 The effect of injecting additional liquid into the arc passage 62 is particularly noticeable during the interruption of arcs of relatively low current magnitude. Under this condition of operation, the slotted magnetic plates 45 exert a relatively weak pull upon the arc and there is a tendency for the arc to remain in the enlarged portion 67 of the arc passage 62, and it does not readily transfer onto the arc horn 99. The effect 70 of the rapid separation of the contact rod 103 from the stationary contact 87 is to produce a pocket in the arc extinguishing liquid between 75 these contacts, which rapidly fills with low pressure gas containing largely ionized particles. The injection of additional arc extinguishing liquid into the arc passage 62 by means of the piston 111 reduces the ionization and raises the 80 pressure in the gas-filled pocket. The injection 85 of additional arc extinguishing liquid under pressure also assists in expelling the gas from the passage through the vent openings 49 and 53.

85 The head plate 75 may also be provided with an aperture 115 in coaxial alignment with the cylindrical passage formed by the tubular member 107, into which a yieldingly mounted valve and stop member 117 projects. The stop member 117 is biased toward the head plate 75 by a spring 119 90 and guided in its movement by a suitable aperture 121 in the bracket 93. The head of piston 111 engages and actuates the stop member 117 to the open position when the piston reaches the end of its strokes during the opening operation 95 of the interrupter thereby permitting further venting of the arc chamber 62 following circuit interruption. The valve and stop member 117 also permits an extinguishing liquid to flow back into the arc chamber to replenish that which was 100 expelled during arc extinction. In the event that the pressure within the arc chamber 62 becomes 105 excessive, we have provided additional vent means in the form of two slot-like ports 123 extending through the head plate 75, on either side 110 of the arc horn 99. The ports 123 register with the inclined side wall portions 73 of the slot 71 positioned in the insulating plate 55. Normally, the ports 123 are covered by a valve plate 125 having a guide rod 127, secured thereto. The rod 115 127 is adapted for sliding movement through a sleeve 129 and aperture 131 in the bracket 93, the sleeve 129 being secured to the bracket 93 in any suitable manner.

120 A pair of coil springs 133 interposed between 125 the bracket 93 and the valve plate 125 normally maintain the latter plate in the valve closing position. In order to prevent the valve plate 125 from rotating about the axis of its guide pin 127, the latter pin is slotted as shown at 135, and the 130 bracket 93 is provided with a transverse pin 137 registering with the slot 135. It will thus be seen that by the selection of springs 133 of suitable tension and also by adjusting the distance of bracket 93 towards and from the head plate 75, 135 the opening of valve plate 125 upon the occurrence of predetermined pressure conditions within the arc chamber 62 may be controlled.

140 Although the right and left-hand arc-extinguishing units 13, as mounted in Fig. 1, are iden- 145

tical in structure, it is believed that the description of the operating mechanism therefor will be clarified by referring to the contact rod of the right-hand unit as 103', and the piston connecting rod of that unit as 113'. The right and left-hand arc-extinguishing units 13 are respectively mounted upon the end plates 11 of the housing 7 so that the contact rod 103 of the left-hand unit is in axial alignment with the piston connecting rod 113' of the right-hand unit and the contact rod 103' of the right-hand unit is in axial alignment with the piston connecting rod 113 of the left-hand unit. The connecting rods 113 and 113' are also provided with reduced threaded end portions 161, which may be screw-threaded into the ends of the respective contact rods 103 and 103', thereby joining each contact rod with a respective connecting rod of the other unit. This construction is more particularly shown in Figs. 1 and 17 to 24.

The base 7 may be utilized to house a suitable driving means, not shown, for actuating a rock shaft 145 having opposed crank arms 147 and 149 secured to one end thereof. Crank arm 149 is coupled by means of an actuating rod 151 to crank arm 153 of the actuating mechanism generally indicated at 9 in Fig. 1.

That part of the mechanism 9 which is directly responsible for actuating the contact rod 103 and its attached piston connecting rod 113' is shown to the right-hand side of section line XIX—XIX of Fig. 17. A side elevation view of this portion of the mechanism in the closed circuit position is shown in Fig. 19. With particular reference to this portion of the mechanism, arm 153 is part of a tubular crank member 155 having a second crank arm 157. The crank member 155 is mounted for rotative movement on pin 159, one end of which is journalled in bracket 161 secured to plate 11, and the other end of the pin is journalled in a cross rib 162 joining the respective end plates 11 of the housing 7. The crank arm 157 is coupled by a pin 165 to a pair of links 167 which in turn are coupled by pin 169 to an actuating arm 171. The lower end of the arm 171 is coupled to contact rod 103 by means of a pin 173. The upper end of arm 171 is provided with a frictionally retained cross pin 175, the ends of which are slidably retained in slots 177 provided in a pair of spaced brackets 179 secured to the upper cross member 180 of the housing 7. A guide arm 181 is pivoted at its lower end by means of pin 183 to two parallel supports 185 secured to the lower cross member 186 of the housing 7. The upper end of guide arm 181 is jointly pivoted with links 167 to the actuating arm 171 by the pin 169.

As crank arm 153 is rotated in a counter-clockwise direction, as viewed in Fig. 19, following the counter-clockwise rotation of rock arm 149, the crank arm 157 through the coupling of links 167, will actuate arm 171 to the right. During this movement coupling pin 169 is rocked in a clockwise direction, as viewed in Fig. 19, with guide arm 181 about the latter's pivot 183. Straight-line motion is, however, obtained of the contact rod 103 by virtue of the fact that the upper end of actuating arm 171 is slidably supported by its cross pin 175 in the slots 177. Thus it is seen that as the operating rod 151 is moved downwardly, contact rod 103 is moved to the open position, or to the right, as shown in Fig. 20, carrying with it the piston connecting rod 113'.

The actuating mechanism which is directly responsible for actuating contact rod 103' of the

right-hand unit and the attached piston connecting rod 113 of the left-hand unit, is shown to the left-hand side of section line XIX—XIX of Fig. 17 as viewed at section line XXI—XXI. A side elevation view of this portion of the mechanism is shown in Fig. 21. The various members of this portion of the actuating mechanism are identical in construction to those previously described and differ only with respect to their disposition within the housing 7. It will be noted that the identical elements shown to the left-hand side of Fig. 17 and in Fig. 21 are reversed with respect to the members previously described.

With particular reference to Figs. 1, 17 and 21, the reference 251 designates an operating rod interconnecting crank arm 147 and crank arm 253. Arm 253 is part of a tubular crank member 255 having a second crank arm 257 secured thereto. The crank member 255 is mounted for rotative movement on pin 259, one end of which is journalled in bracket 261 secured to the left-hand plate 11, and the other end of which is journalled in a cross rib 263 joining the respective end plates 11 of the housing 7.

The crank arm 257 is coupled by a pin 265 to a pair of links 267 which, in turn, are coupled by pin 269 to an actuating arm 271. The upper end of arm 271 is coupled to the contact rod 103' by means of a pin 273. The lower end of arm 271 is provided with a frictionally retained cross pin 30 275, the ends of which are slidably retained in slots 277 provided in a pair of spaced brackets 279 secured to the lower cross member 186 of the housing 7.

A guide arm 281 is pivoted at its upper end by 35 means of a pin 283 to two parallel supports 285 secured to the upper cross member 180 of the housing 7. The lower end of guide arm 281 is jointly pivoted with links 267 to the actuating arm 271 by the pin 269.

As crank arm 253 is rotated in a counter-clockwise direction about its pivotal axis 259, as a result of upward movement of the operating rod 251, crank arm 257, through the medium of the coupling links 267, will actuate arm 271 to the left, to the open circuit position as shown in Fig. 22, carrying with it the contact rod 103', and consequently, the attached piston connecting rod 113. Straight-line movement of contact rod 103' and connecting rod 113 is obtained in the 50 manner previously described in connection with the actuating mechanism for contact rod 103 and the attached connecting rod 113'. Inasmuch as actuating rods 151 and 251 are coupled for simultaneous actuation to the respective crank arms 149 and 147, it is apparent that the contact rods and piston connecting rods of both the right and left-hand units 13 will be actuated simultaneously to either the open or closed position.

In order to further balance the reactive forces 60 between the respective contact rods and piston connecting rods, we have provided as shown in Figures 17, 23 and 24, an interconnecting linkage which consists of a pair of levers 290 centrally pivoted about a pin 291, the ends of which are 65 respectively journalled in cross ribs 163 and 263. The upper ends of levers 290 are pivotally coupled to a pair of links 293 by a pin 295, and the other ends of links 293 are, in turn, jointly pivoted with actuating arm 271 to the contact rod 103' by means of the pin 273.

The lower ends of levers 290 are pivotally jointed to a pair of links 297 by means of a pin 299. The links 297 are in turn pivotally joined with the actuating arm 271 to the contact rod 75

103 by means of the pin 173. Fig. 23 shows the equalizing linkages in the closed circuit position whereas Fig. 24 shows the linkage in the open circuit position. It will thus be seen that any 5 reciprocating movement of one contact rod and its attached piston connecting rod will be transmitted through the linkage to the other contact rod and its attached piston connecting rod.

In order to establish a series electrical circuit 10 through the interrupter, contact rod 103 is connected by means of a flexible conductor 301 to the contact rod 103'. The electrical circuit through the left-hand arc extinguishing unit 13 proceeds from the flexible conductor 301 to the 15 movable contact rod 103 to the fixed contact 81, contact support 89, the flexible conductor 303, terminal 305, flexible conductor 307 and the external terminal 309. The terminal 309 is mounted in an end bell or cover 311, which end 20 bell is supported from the end plate 19. The electrical circuit through the right-hand arc extinguishing unit 13, not shown, is identical with that described in the left-hand unit.

Although we have shown and described a particular 25 circuit interrupting structure and have shown specific detailed arrangements of the arc extinguishing units therein, it is to be understood that the same is for the purpose of illustration and that changes may be made by those 30 skilled in the art without departing from the spirit and scope of the appended claims.

We claim as our invention:

1. In a circuit interrupter, means defining an 35 arc passage, an arc extinguishing liquid within said passage, means for establishing an arc within said passage, means for moving said arc laterally within said passage and means for moving additional arc extinguishing liquid through said arc in a direction opposite to said arc 40 movement.

2. In a circuit interrupter, a body of arc extinguishing liquid, means of insulating material defining an arc passage immersed in said liquid, said means of insulating material having pockets 45 along the sides of said passage for trapping a considerable quantity of said liquid, separable contacts for establishing an arc within said passage, means for moving said arc laterally into close proximity with said entrapped liquid and 50 means for positively moving additional liquid through said arc in a direction opposite to said arc movement.

3. In a circuit interrupter, a body of arc extinguishing liquid, means of insulating material defining an arc passage immersed in said liquid, said means of insulating material having pockets along the sides of said passage for trapping a considerable quantity of said liquid, separable contacts for establishing an arc within said 55 passage, means for moving said arc laterally into close proximity with said entrapped liquid, means for positively moving additional liquid through said arc in a direction opposite to said arc movement, and means for causing the products of 60 decomposition of said arc and quantities of said additional liquid to normally escape from said passage only through the arc stream.

4. In a circuit interrupter, means of insulating material defining an arc passage, said passage 65 having an enlarged entrance portion and a constricted portion, an arc extinguishing liquid within said passage, means for establishing an arc in said entrance portion, magnetic means for moving said arc laterally into said constricted portion, and means for positively moving an addi- 70

tional quantity of arc extinguishing liquid along said passage into and through the arc stream in a direction opposite to that of arc movement.

5. In a circuit interrupter, means of insulating material defining an arc passage, said passage 75 having an enlarged entrance portion and a constricted portion, an arc extinguishing liquid within said passage, means for establishing an arc in said entrance portion, magnetic means for moving said arc laterally into said constricted portion, and means for positively moving an additional quantity of arc extinguishing liquid along said passage through said arc in a direction towards said entrance portion of said arc passage. 10

6. In a circuit interrupter, means of insulating material defining an arc passage, said passage having an enlarged entrance portion and a constricted portion, an arc extinguishing liquid within said passage, means for establishing an arc in said entrance portion, magnetic means for moving said arc into said constricted portion, means for positively moving an additional quantity of arc extinguishing liquid along said passage through said arc in a direction towards said entrance portion of said arc passage, and means 15 for venting said passage adjacent said enlarged entrance portion to cause liquid and any products of decomposition of said arc from said constricted portion of the arc passage to flow through the arc stream. 20

7. In a circuit interrupter, means of insulating material defining an arc passage, a stationary contact within said passage, a movable contact adapted to cooperates with said stationary contact for drawing an arc within said passage, an arc extinguishing liquid within said passage, means for moving said arc laterally within said passage, means for positively moving a quantity of arc extinguishing liquid through said arc in a direction opposite to that of arc movement, 30 and actuating means for simultaneously operating said movable contact to establish the arc and operating said means for positively moving a quantity of arc extinguishing liquid through the arc stream. 35

8. In a circuit interrupter, a body of arc extinguishing liquid, means of insulating material defining an arc passage immersed in said liquid, a stationary contact within said passage, a co-operating contact movable to open and closed 40 positions, means for moving the arc established upon movement of said cooperating contact to the open position laterally along said passage, means operative in response to movement of said cooperating contact to the open position for positively moving a quantity of arc extinguishing liquid into said arc passage and through said arc in a direction opposite to that of arc movement, vent means adjacent said stationary contact for the escape of gas and arc extinguishing 45 liquid from said arc passage and additional means operative in response to predetermined pressure conditions within said arc passage for controlling the escape of gas and arc extinguishing liquid from said passage. 50

9. In a circuit interrupter, a body of arc extinguishing liquid, an arc extinguishing structure adapted to be immersed therein, said arc extinguishing structure comprising a plurality of plates of insulating material disposed in contiguous relation, a plurality of said plates having slots therein to form a substantially completely enclosed arc passage, a pair of separable contacts within said passage for establishing an arc therein, an arc horn adjacent at least one end 55

- of said arc passage, a plurality of slotted plates of magnetic material embedded in certain of said plates of insulating material for moving the arc along said passage with one end thereof in contact with said arc horn, and means operative in response to the opening movement of one of said contacts for positively directing a stream of arc extinguishing liquid along said arc horn through said arc in a direction opposite to that of arc movement, at least one of said plates of insulating material adjacent said arc horn having an open-end slot adjacent said contacts for causing arc extinguishing liquid and gas escaping from the passage to pass through the arc stream.
15. 10. In a circuit interrupter, a body of arc extinguishing liquid, means of insulating material immersed in said liquid defining a narrow arc chamber and a cylindrical passage communicating with said arc chamber at one side thereof, a piston movable in said passage, a stationary contact extending into said arc chamber adjacent the opposite side thereof, a cooperating contact movable to establish an arc within said arc chamber, means for moving said arc within said chamber, and an actuating mechanism for operating said movable contact to establish the arc and for operating said piston to move a quantity of liquid out of said passage into said chamber in a direction opposite to that of arc movement.
20. 11. In a circuit interrupter, a body of arc extinguishing liquid, means of insulating material immersed in said liquid defining a narrow arc chamber and a passage communicating with said arc chamber at one side thereof, a piston movable in said passage, a stationary contact extending into said arc chamber adjacent the opposite side thereof, a cooperating contact movable to establish an arc within said arc chamber, means for moving said arc within said chamber, an actuating mechanism for operating said movable contact to establish the arc and for operating said piston to move a quantity of liquid out of said passage into said chamber in a direction opposite to that of arc movement, and vent means adjacent said stationary contact to cause gas generated by the action of said arc upon said liquid to flow through the arc stream in escaping from the arc chamber.
25. 12. In a circuit interrupter, a body of arc extinguishing liquid, means of insulating material immersed in said liquid defining a narrow arc chamber and a passage communicating with said arc chamber at one side thereof, a piston movable in said passage, a stationary contact extending into said arc chamber adjacent the opposite side thereof, a cooperating contact movable to establish an arc within said arc chamber, means for moving said arc within said chamber, an actuating mechanism for operating said movable contact to establish the arc and for operating said piston to move a quantity of liquid out of said passage into said chamber in a direction opposite to that of arc movement, said actuating mechanism including a linkage for balancing the reactive forces exerted upon said movable contact and said piston due to the pressure created by said arc within said chamber.
30. 13. In a circuit interrupter, a body of arc extinguishing liquid, means of insulating material immersed in said liquid defining an arc passage and a cylindrical passage adjacent thereto, said means of insulating material having an opening leading from said arc passage to said cylindrical passage adjacent at least one end thereof, a piston movable in said cylindrical passage, a pair

of contacts one of which is movable to establish an arc within said arc passage, means for moving the arc along said arc passage toward said opening, and an actuating mechanism for said movable contact and said piston, said actuating mechanism comprising a linkage normally maintaining said piston in liquid discharging position when said movable contact is in the closed position, said linkage operating said piston to discharge liquid from said cylindrical passage into said arc passage through said opening when said movable contact is actuated to the open position.

14. A circuit interrupter comprising a casing containing arc extinguishing liquid, a pair of arc extinguishing units immersed in said liquid, each of said units including an arc passage, a pair of separable contacts to establish an arc in said passage, a second passage communicating with said arc passage, a piston movable in said second passage to positively inject arc extinguishing liquid into said arc passage, a movable contact carrying member for one of said contacts of said pair of contacts, and a connecting rod for said piston, means supporting said arc extinguishing units in opposed spaced relation, means directly coupling said contact carrying member of each unit with said connecting rod of a respective other unit, an actuating mechanism disposed between said arc extinguishing units for simultaneously operating said contact carrying members to establish an arc in each arc extinguishing unit, and for simultaneously operating said connecting rods to cause said pistons to inject arc extinguishing liquid into the arc stream within said arc extinguishing units.

15. A circuit interrupter comprising a casing containing arc extinguishing liquid, a pair of arc extinguishing units disposed in opposed spaced relation and immersed in said liquid, each of said units having an arc chamber, means for establishing an arc in each chamber including a contact rod for each unit slidable through the respective adjacent ends thereof, each of said units having a cylindrical passage communicating with its arc chamber, a piston movable in each cylindrical passage and having a connecting rod secured thereto and slidable through said respective adjacent ends of said units, a contact rod of one unit being axially aligned with the connecting rod of the other unit and coupled thereto for movement therewith, and an actuating mechanism for simultaneously moving said contact rods to establish an arc within each arc chamber, said pistons being simultaneously actuated in response to said movement of said contact rods to inject a quantity of arc extinguishing liquid into each arc chamber to aid in the extinction of said arc.

16. A circuit interrupter comprising a casing containing arc-extinguishing liquid, a pair of arc-extinguishing units disposed in opposed spaced relation and immersed in said liquid, each of said units having an arc chamber, a pair of contacts within said chamber, one of which is movable for establishing an arc, a cylindrical chamber communicating with said arc chamber and a piston movable within said cylindrical chamber to force additional arc-extinguishing liquid into said arc chamber, means directly connecting the piston of one unit to the movable contact of the other unit and the movable contact of the said one unit to the piston of said other unit, and actuating means for simultaneously operating said pistons and movable contacts, said actuating mechanism including a linkage for balancing the reactive forces exerted upon said movable contacts and

said pistons due to the pressure created within the respective arc chambers.

17. In a circuit interrupter, a body of arc-extinguishing liquid, means of insulating material immersed in said liquid defining a narrow substantially enclosed arc chamber, means for establishing an arc within said arc chamber, an arc terminal member adjacent at least one end of said arc chamber, means for moving the arc along said arc chamber with one end thereof in contact with said arc terminal member, means operative in response to the establishment of an arc for positively directing a stream of arc-extinguishing liquid along said arc terminal member in a direction opposite to that of arc movement, and vent means disposed adjacent said separable contacts for causing arc-extinguishing liquid and gas escaping from the arc chamber to pass through the arc stream.

18. In a circuit interrupter, a body of arc-extinguishing liquid, means of insulating material immersed in said liquid defining a substantially enclosed slot-like arc passage, separable contacts for establishing an arc within said arc passage, an arc horn adjacent at least one end of said arc passage, magnetic means for moving the arc laterally within said passage with one end thereof in contact with said arc horn, means operative in response to the opening movement of said contacts for injecting an additional quantity of arc-extinguishing liquid into said passage and directing it along said arc horn in a direction opposite to that of arc movement, and means adjacent

said arc horn operative in response to predetermined pressure conditions within said arc passage for controlling the escape of gas and arc-extinguishing liquid from said passage.

19. In a circuit interrupter, a body of arc-extinguishing liquid, means immersed in said liquid defining a substantially enclosed arc passage, means for establishing an arc within said passage, means for positively injecting an additional quantity of arc-extinguishing liquid into said arc passage and through the arc stream, and means for controlling the flow of arc-extinguishing liquid into said arc chamber, said last-named means being actuated by said liquid injecting means to cause arc-extinguishing liquid to flow into said arc passage following actuation of the interrupter to the open circuit position.

20. In a circuit interrupter, a body of arc-extinguishing liquid, means immersed in said liquid defining a substantially enclosed arc passage, means for establishing an arc within said passage, a piston for injecting an additional quantity of arc-extinguishing liquid into said arc passage and through the arc stream, and normally closed valve means for controlling the flow of arc-extinguishing liquid into said arc passage, said valve means being actuated to the open position by said piston to admit liquid into said arc passage when the interrupter has been actuated to the open circuit position.
